UNITED STATES PATENT OFFICE.

ARCHIBALD CHARLES HEAPHY, OF NEW YORK, N. Y.

WARDROBE ATTACHMENT FOR CHAIRS.

1,375,047.

Specification of Letters Patent. Patented Apr. 19, 1921.

Application filed July 7, 1919. Serial No. 309,002.

To all whom it may concern:

Be it known that I, ARCHIBALD C. HEAPHY, a citizen of the United States, residing at New York, in the county of New York and 5 State of New York, have invented certain new and useful Improvements in Wardrobe Attachments for Chairs, of which the following is a specification.

This invention pertains to wardrobe attachments for chairs, the construction and advantages of which will be hereinafter set forth in detail. The installation of lockers in offices, or the provision of locker rooms in buildings, is attendant with certain objections, among which may be mentioned the taking up of valuable floor space, the expense necessary to their installation and the congestion and confusion and consequent delay of the employees when assembling to dispose of or receive their wraps.

The object of the present invention is to provide means whereby such locker systems may be done away with and to that end I have produced a wardrobe designed to hold 25 the head coverings and wraps of an individual, which wardrobe may be readily attached to an ordinary chair. The construction is such that it occupies a minimum of space and does not in any wise interfere 30 with the ordinary use of the chair, as, for instance, the turning of the seat upon its swivel or screw, or the tilting thereof, if the device be employed in conjunction with a chair of the screw and tilting back type.

35 One embodiment of the invention is disclosed in the annexed drawings, wherein:

Figure 1 is a side elevation of a chair showing the wardrobe attached thereto and in its closed position;

40 Fig. 2 a vertical sectional view with the wardrobe opened;

Fig. 3 a plan view of the lower compartment, viewed in its open position;

Fig. 4 a transverse vertical sectional view 45 taken on the line IV—IV of Fig. 2;

Fig. 5 a side elevation of the lower wardrobe member showing the same in its lowered position with the clothes retaining rods thrown upwardly; and

50 Fig. 6 a vertical sectional view thereof with the rods in the same relation as in Fig. 5.

In said drawings, 1 denotes the chair base, 2 the screw pedestal and 3 the seat, the 55 chair having a back comprising the usual uprights or spindles 4 and the cross bar 5.

The wardrobe may be said to comprise two compartments or receptacles, one for the hat and the other for the coat or wrap, the latter being provided with means for 60 engaging the coat and holding it in a folded condition within the receptacle. In the present instance to produce the wardrobe there is provided a body or fixed closure element 6 having a pair of hook shaped 65 members 7 which latter engage the bar 5 and hold the element 6 in rear of and against the chair back. Hinged to the upper end of the body 6 is a box-like element 8 forming the hat compartment. Suitable 70 hat retaining means as 9 is secured to the upper rear face of the closure or body element, and when the box 8 is swung down to its closed position its edges abut the body 6 and thus forms a closed compartment in 75 which the hat is housed and inclosed.

Secured to the under rear portion of the seat 3 is a pair of plates or hinge members 10 between the rear ends of which is pivotally mounted the clothes compartment, 80 said element likewise taking the form of a box, as 11. Said compartment is of such length that when in its closed position, Fig. 1, it abuts the lower face of the compartment 8. In order that the wrap or coat may be 85 held in the compartment and this without undue creasing, I provide a series of rods which extend transversely of the compartment. The outer or uppermost rod is designated by 12, and is hinged to one of the 90 side walls, as at 13, the free end when it is turned down engaging a friction latch of any approved type, as 14, to hold the rod in place.

A second rod 15, located centrally of the 95 compartment and in a plane above the rod 12, is mounted in a similar manner. A third rod 16 is located in the lower or inner end of the compartment. Said rod is pivoted at one end to a slide 17 mounted in a slot 100 18, Figs. 5 and 6, formed in the side wall of the member 11, the slide being formed with a finger piece or hand hold so that it may be moved along the slot. The free end of said rod 16 will when it is brought to its 105 final innermost position engage a friction lock and thus be held against movement. With the rods thus arranged a folded garment may be held in position within the compartment, as shown in dotted lines in 110 Fig. 2. The central portion of the garment will be laid within the compartment, see

Fig. 6, at which time all the rods will stand vertical. Rod 12 will be turned down over the garment and rod 16 likewise, and the latter will then be shifted bodily to the 5 position shown in Fig. 2. The upstanding end portions of the garment will then be turned in and the central rod 15, which may be termed a compression rod or member, will then be turned down, said rod overlying 10 the infolded end portions of the garment (Fig. 2) and thus hold it against shifting as the compartment is turned into its upright position in rear of the chair back and against the fixed closure member 6.

15 To prevent the chair from tipping over when the clothes compartment is lowered, I preferably provide a support therefor, shown in the present instance as a pair of legs 19, said legs being pivoted to the side 20 walls of the compartment. The legs are of a length to touch and rest upon the floor when the compartment comes to the horizontal position, and locking means, such as rods 20, pivoted at one end to the legs and 25 adapted to pass into sockets 21 carried by the compartment, will be employed to hold the legs against accidental displacement.

The compartments may be provided with suitable locks, or a single lock, as indicated 30 in Fig. 1, may be employed.

It will be manifest that instead of employing the suspending members 7 that the body or closure element 6 may be secured directly to the rear face of the cross bar 5 and to the 35 seat by suitable fastening devices, such as screws 22, shown in Fig. 2.

What is claimed is,—

1. In a wardrobe attachment for chairs, the combination of a body member adapted 40 to be secured to a chair back and in rear thereof; and two box-like members associated therewith and adapted when closed against the body member to form compartments in which wearing apparel may be 45 housed.

2. In a wardrobe attachment for chairs, the combination of a body member adapted to be secured to a chair back and in rear thereof; and two hinged box-like members 50 associated therewith, said members when closed against the body member forming compartments for the storage of wearing apparel.

3. In a combined chair and wardrobe, the 55 combination of a chair; a closure member attached to the rear of the back thereof; hat sustaining means attached to the upper rear

portion of said member; a box-like structure hinged to the upper end of the closure member and adapted to swing downwardly and 60 inclose said hat sustaining member; a second box-like structure pivotally supported adjacent the lower portion of the chair and adapted to be turned upwardly into closed position with reference to the closure member; and means carried by said second box-like structure for maintaining a wrap in position therein.

4. In a combined chair and wardrobe, the combination of a chair; a box-like member 70 pivotally mounted adjacent the lower portion of the chair and adapted to be swung upwardly in rear thereof; a plurality of rods pivotally mounted within said member and extending transversely thereof when 75 turned down therein; a slide mounted in a way in the side wall of said box-like member; and a rod pivoted to the inner end of said slide.

5. In a wardrobe, the combination of a 80 compartment adapted to receive a garment in a folded condition; and a plurality of rods mounted for swinging movement across and into said compartment, one of said rods being bodily shiftable toward the others. 85

6. In a wardrobe, the combination of a compartment adapted to receive a garment in a folded condition; a rod located within and at one end of the compartment and extending across the same; a rod located at and 90 within the opposite end of the compartment, said rod being bodily shiftable toward and from the first named rod; and a third rod hinged to the inner face of the compartment at a point intermediate said other rods. 95

7. In a wardrobe, the combination of a compartment adapted to receive a garment in a folded condition; a rod hinged within and at one end of the compartment and extending across the same; a slide located adjacent the opposite end of the compartment; a rod hinged to the inner portion of said slide, said rods being adapted to have a garment placed below the same with the ends of the garment folded back about and above the rods; and a third hinged rod lying in a plane above that occupied by the others and adapted to be swung inwardly against the infolded ends of the garment to retain the same in place. 105 110

In testimony whereof I have signed my name to this specification.

ARCHIBALD CHARLES HEAPHY.
